UNITED STATES PATENT OFFICE.

KARL ENGEL, OF ARLINGTON, MASSACHUSETTS, ASSIGNOR TO UNITED SHOE MACHINERY COMPANY, OF PATERSON, NEW JERSEY, A CORPORATION OF NEW JERSEY.

PROCESS OF MAKING SHOE-UPPERS.

1,139,653.

Specification of Letters Patent.

Patented May 18, 1915.

Application filed December 21, 1912. Serial No. 738,025.

To all whom it may concern:

Be it known that I, KARL ENGEL, a citizen of the United States, residing at Arlington, in the county of Middlesex and State of Massachusetts, have invented certain Improvements in Processes of Making Shoe-Uppers, of which the following description, in connection with the accompanying drawings, is a specification, like reference characters on the drawings indicating like parts in the several figures.

This invention relates to the manufacture of shoes and the object is to provide an improvement in the art of constructing the upper portion of a shoe, whereby the material may be used economically and to the best advantage to secure a product which is strong, durable and neat in appearance.

A shoe upper made according to this process includes a vamp with side portions extended rearwardly to the vicinity of the heel and secured at their ends to an insertion which completes the heel portion.

The invention contemplates also the production of a shoe in which quarters are secured to the vamp at the ankle opening, with an upward projection of the heel insertion piece secured to the quarters as a back-stay and conveniently extending also above the quarters to form a strap, such a shoe including in the vamp a throat opening in which eyelet pieces are inserted.

In practising the method a vamp blank is formed with side portions suitably extended and shaped at their ends for attachment to an insertion at the heel, and this blank is provided with an ankle opening by removing a piece of material shaped at its sides for attachment to the ends of the vamp extensions. The shape of the piece cut out is determined with reference to the desired contour of the upper edges of the vamp extensions in the completed shoe, as well as with reference to the suitability of the piece for use as an insertion to give the shoe a proper shape at the heel end, and with these considerations in view the shape of the piece may be varied considerably, the contour of the ends of the vamp extensions being suitably varied to correspond. The width of the piece also depends principally upon the width or height desirable for the side extensions of the vamp, and the method permits considerable variation also in this respect without entailing any waste of material,

since the length of the vamp extensions may be suitably varied to accommodate them to the width of the insertion piece.

In carrying out the method for the production of a shoe having quarters secured to the vamp, the vamp blank is preferably further provided with a throat opening in addition to the ankle opening, and these openings are formed by the removal of material shaped to serve as the heel insertion referred to and also to provide a back-stay for the quarters, and preferably also a strap portion arranged to project above the quarters. The back-stay and strap similarly to the heel insertion may be varied somewhat in shape and size with reference both to their subsequent use in the shoe and to the shape of the edges of the vamp at the throat opening. It will be seen that the method thus permits considerable variation in the shape and proportions of the different parts without involving waste of material, since any such change in one of the parts entails simply a corresponding change in another, and all the material is preserved and utilized to the best advantage.

The invention will be explained in greater detail with reference to the accompanying drawings, in which—

Figure 1 represents a vamp blank with the openings therein and shows the manner in which the heel insertion, back stay and strap correspond to the openings, and Figs. 2 and 3 are respectively a side view and a rear view of a shoe upper constructed in accordance with my process.

I first cut a vamp blank 1, extended to provide side portions 2 and 3 suitably curved at their ends, as indicated at 4 and 5, with a view to the proper shape and appearance of the shoe when these ends are stitched to the sides of a heel insertion. I next provide the vamp blank with an ankle opening and a throat opening, and I find it both feasible and convenient to shape these openings in such a way that the material removed to form the ankle opening shall be of the proper shape for attachment to the side extensions of the vamp to form the heel insertion, and the material removed to form the throat opening shall be properly shaped to serve as a back-stay for the quarters of the upper, and if desired also, to provide a strap projecting above the quarters. The heel insertion is indicated

at 6, the back-stay at 7, and the strap portion at 8. In practice I prefer, for the sake of the appearance of the shoe, to extend the side lines of the narrow part of the back-stay in curves to the sides of the heel insertion, as indicated at 9 and 10 although this is not essential. With this form I attach the insertion 6 to the ends 4 and 5 in such a way that the curves 9 and 10 meet the ends of the boundary lines of the upper sides of the extensions 2 and 3, as shown in Figs. 2 and 3. The insertion 6 is preferably so shaped at its sides as to conform to the contour of the curved ends 4 and 5 at those portions intended for attachment to said ends, and these curves are the same at both sides of the respective blanks.

From the preceding description the manner of assembling the essential parts of the upper will be evident. The quarters 11 are sewed to the vamp at the ankle opening, and the back-stay 7 is stitched to the quarters, leaving the strap 8 projecting thereabove. In the throat opening are sewed the eyelet pieces 12 which may be cut conveniently from small scraps of material that would otherwise be wasted. These pieces, however, may be formed integral with the quarters if desired.

As will be evident from an inspection of the drawings, the ends 4 and 5 of the side portions of the vamp blank are convexly curved and so cut as to leave these side portions of greater longitudinal extent near their outer edges, and the insertion piece 6 is correspondingly curved at its sides and narrowed toward the rear portion of the blank where it is intended to fit between these longer and more closely approaching portions of the vamp extensions near the bottom of the shoe. As a result of proportioning and correlating the parts in this manner, the rear lower portion of the upper will be suitably curved or hollowed about the heel of the wearer's foot, and the upper edges of the side portions 2 and 3 will extend in a graceful upward curve toward the rear, thereby presenting an attractive appearance in the completed shoe and assuring that these side portions at the rear shall be wide enough to extend above the heels to the vicinity of the ankle.

It will be seen that the only waste of stock within the outline of the vamp blank by my process comprises the small bits of leather between the curves 9 and 10 and the sides of the ankle opening, and the small piece 13 that may be cut from the strap. It may be necessary also, in addition to the trimming operation at the curves 9 and 10, to trim off a tip of the heel insertion 6 so that the side contour lines from the ends of the curves 9 and 10 to the end of the insertion piece may equal in length the lines marking the ends of the vamp extensions; but

for some sizes of shoe there will be practically no such waste and in any case it is negligible. In this connection it should be noted that the size of the vamp may be varied within wide limits without varying the size of the ankle and throat openings or the portions of material to be used as heel insertion, back-stay and strap. This makes it especially convenient to cut these portions by means of a die, since one such die may be used for several sizes of vamps. It will be understood, however, that the blanks may be cut and the openings formed by any means desired.

Other modifications of the process also within the spirit and scope of the appended claims will occur to those skilled in the art to which my invention applies.

Having described my improved process and the preferred manner of giving the same practical effect, what I claim and desire to secure by Letters Patent of the United States is the following:

1. That improvement in the art of making shoe uppers which consists in forming a vamp blank extended to provide side portions of suitable length and end contour for attachment to an insertion of predetermined shape and size at the heel of the shoe, providing said blank with an ankle opening by removing a piece of material of said predetermined shape and size to serve as said insertion and suitably proportioned to leave the side extensions of the vamp of the desired width and edge contour at the ankle opening, and securing said piece at its sides to the ends of said extensions to complete the heel portion of the upper.

2. That improvement in the art of making shoe uppers which consists in forming a vamp blank extended to provide side portions of suitable length for attachment to an insertion of predetermined width at the heel of the shoe and of an end contour conformable to the predetermined contour of the sides of said insertion, providing said blank with an ankle opening by removing a piece of material of the predetermined width and shape to serve as said insertion and having its sides convexly curved so as to insure a suitable curve at the rear end face of the heel of the completed shoe and provide a suitable outline for the upper edge portions of the vamp extensions, and securing said piece at its sides to the ends of said extensions to complete the heel portion of the upper.

3. That improvement in the art of making shoe uppers which consists in forming a vamp blank extended to provide side portions of suitable length and end contour for attachment to an insertion of predetermined shape and size at the heel of the shoe, providing said blank with an ankle opening by removing a piece of material of prede-

terminated shape and size to serve as said insertion and suitably proportioned to leave the side extensions of the vamp of the desired width and with the edges of said extensions at the ankle opening suitably shaped to incline upwardly toward the rear of the completed shoe, and securing said piece at its sides to the ends of said extensions to complete the heel portion of the upper.

4. That improvement in the art of making shoe uppers which consists in forming a vamp blank extended to provide side portions shaped for attachment at their ends to an insertion at the heel of the shoe, providing said blank with an ankle opening and a throat opening by removing portions of material shaped respectively for attachment to said extensions as the heel insertion and to serve as a back-stay, and uniting said heel insertion to said extensions and the back-stay to the quarters of the upper.

5. That improvement in the art of making shoe uppers which consists in forming a vamp blank extended to provide side portions shaped for attachment at their ends to an insertion at the heel of the shoe, providing said blank with an ankle opening and a throat opening by removing portions of material shaped respectively for attachment to said extensions as the heel insertion and to serve as a back-stay and strap, and uniting said heel insertion to said extensions and the back-stay to the quarters of the upper with the strap portion projecting above said quarters.

6. That improvement in the art of making shoe uppers which consists in forming a vamp blank extended to provide side por-

tions shaped for attachment at their ends to an insertion at the heel of the shoe, providing said blank with an ankle opening and a throat opening by removing a piece of material the respective portions of which are shaped for attachment to said extensions as the heel insertion and to serve as a back-stay and strap, trimming said piece of material to limit the length of the side contour lines of said heel insertion to the length of the contour lines at the ends of the respective extensions after said piece has been removed, and uniting the heel insertion to said extensions and the back-stay to the quarters of the upper with the strap projecting above said quarters.

7. That improvement in the art of making shoe uppers which consists in forming a vamp blank extended to provide side portions shaped for attachment at their ends to an insertion at the heel of the shoe, providing said blank with an ankle opening and a throat opening by removing a piece of material the respective portions of which are shaped for attachment to said extensions as the heel insertion and to serve as a back-stay and strap, extending the side lines of the back-stay portion in curves to the sides of the heel insertion, and uniting the heel insertion to said extensions and the back-stay to the quarters of the upper with the strap projecting above said quarters.

In testimony whereof I have signed my name to this specification in the presence of two subscribing witnesses.

KARL ENGEL.
